US00D882750S

(12) **United States Design Patent** (10) Patent No.: **US D882,750 S**
(45) Date of Patent: **** Apr. 28, 2020**

(54) **EXHAUST PIPE PROTECTION**

(71) Applicant: **POLISPORT PLÁSTICOS, SA,**
Fontanheira Carregosa (PT)

(72) Inventor: **Pedro Jorge Pinto Oliveira Araújo,**
Vale de Cambra (PT)

(**) Term: **15 Years**

(21) Appl. No.: **35/506,558**

(22) Filed: **Oct. 10, 2018**

(80) **Hague Agreement Data**

Int. Filing Date: **Oct. 10, 2018**

Int. Reg. No.: **DM/103751**

Int. Reg. Date: **Oct. 10, 2018**

Int. Reg. Pub. Date: **Apr. 12, 2019**

(57) **CLAIM**

The ornamental design for exhaust pipe protection, as shown and described.

DESCRIPTION

1. Exhaust pipe protection

1.1 : Top

1.2 : Front

1.3 : Left

1.4 : Perspective

1.5 : Bottom

1.6 : Right

1.7 : Back

Views 1.2 and 1.7 are identical opposite views.
